UNITED STATES PATENT OFFICE.

EDMUND F. HARTSHORN, OF NEWARK, NEW JERSEY, ASSIGNOR TO THE STEWART HARTSHORN COMPANY, OF NEW JERSEY.

SPRING SHADE-ROLLER:

SPECIFICATION forming part of Letters Patent No. 654,893, dated July 31, 1900.

Application filed May 3, 1900. Serial No. 15,317. (No model.)

To all whom it may concern:

Be it known that I, EDMUND F. HARTSHORN, a citizen of the United States of America, and a resident of Newark, county of Essex, State 5 of New Jersey, have invented certain new and useful Improvements in Spring Shade-Rollers, of which the following is a specification.

This invention relates to a novel method of attaching the coiled spring mounted on the 10 spindle to the metal spindle tip or "spear" connected to the end of the spindle, the outer end of which enters the square or notched window-bracket and holds the spindle stationary as the roller turns around it under the 15 manipulation of the shade. Heretofore the methods adopted for attaching the end of the spring to the spindle in this form of spring-roller were either by thrusting the end of the spring through a hole formed in the end of 20 the wooden spindle and a similar hole formed in the end of the spindle-tip inserted in the end of the spindle and bending the spring around the spindle or by thrusting the end of the spring through a hole cast or punched in 25 the metal spindle-tip beyond the end of the wooden spindle and tying it by bending it at that point. In these methods of tying or fastening the end of the spring it is necessary to manipulate or bend the spring in such manner 30 as to disarrange its natural cycloidal curves, preventing the best results in the operation of the roller and causing the construction to be less economical than by the method here described. In this improvement the 35 spring is attached to the spindle just as it comes from the mandrel around which it is coiled and is held between the forked ends of the spindle-tip, as described below, by which the latter is connected to the spindle and all 40 manipulation or bending of the spring is avoided, and, furthermore, the desirable metallic bearing is furnished for the spring under all circumstances.

In the accompanying drawings, forming 45 part of this specification, Figure 1 is a complete view of the spindle and spring and spindle-tip connected thereto, showing the improved method of attaching the end of the spring to the spindle and one of the usual 50 methods of attaching the other end of the spring to the bore of the roller. Fig. 2 is a

transverse section of Fig. 1 through the line 2 2. Fig. 3 is a view of the end of the coiled spring. Fig. 4 is a view of the end of the spindle and spindle-tip and spring, showing 55 a modified construction of the spindle and attachment of the spring. Fig. 5 is a transverse section of Fig. 4 through the line 5 5. Fig. 6 is the same as Fig. 4, showing a folded spindle-tip; and Fig. 7 is a detached view of 60 the spindle and spindle-tip shown in Fig. 6. 1 is the spindle.

3 is the spring as it comes from the mandrel, having its outer end 4 bent across the plane of its coils, as shown in Fig. 4, and 5 is 65 the spindle-tip.

In assembling the parts the spindle is inserted in the coiled spring at the inner end of the latter or end opposite the bent end 4 and pushed through until the bent end 4 rests on 70 the end of the spindle or enters the cleft 2 in the end of the spindle in the modified construction shown in Figs. 4 and 6. The other or inner end 6 of the spring in the construction shown in the drawings is then attached 75 to the metal bung 7, in which the spindle loosely rests, and which is fastened to the roller within the bore of the latter by the prongs 8.

To the outer end of the spindle is connected the spindle-tip 5, which in this improvement 80 is provided with two forked projections 9, which fit over the end of the spindle and serve to attach the tip to the latter. This forked spindle-tip may be cast ready for attaching to the spindle, as in Figs. 1 to 5, or folded 85 from a sheet-metal blank, as in the constructions shown in Figs. 6 and 7. As the spindle-tip is connected to the spindle the forked projections 9 are placed over the end of the latter in such manner as to embrace the end 90 4 of the spring resting on the end of the spindle or cause it to lie between them, as shown in Figs. 1 and 2. The end of the spring is now held between the forks of the spindle-tip, so as to impinge or bear against the forks under 95 the operation of the spring, and the attachment of the spring to the spindle is complete. The operation of connecting the spindle-tip to the spindle thus fastens or ties the spring to the latter, and the attachment is 100 effected without the necessity of manipulating the spring in any manner.

In the case of the modified construction shown in Figs. 4, 5, and 6, where the end of the spring rests in a cleft in the end of the spindle, the forked projections 9 of the spindle-tip are so placed on the spindle as to extend along the edges of the cleft, as shown in the drawings, and in such manner that the spring in the cleft bears or impinges against their opposite edges, Fig. 5, and the spring is thus held by the forked projections, as in the former construction shown in Fig. 1. Where the spring is thus held by the forked projections on each side of the cleft, the splitting of the spindle by the spring, which was apt to occur when the spring was held merely by the cleft in the previous construction, is avoided.

In the folded spindle-tip shown in Figs. 6 and 7 the tip is attached to the spindle not only by the projecting ends 9, but by the inner web 10 of the tip, which fits into the cleft 2 in the spindle. As will be seen from Fig. 6, the opposite edges 11 of the projecting ends 9 are so constructed that when the tip is in place on the end of the spindle, with the web 10 in the cleft in the latter, these edges 11 will lie along the edges of the cleft around which the spring curves and in such manner that the spring bears or impinges against their opposite edges. In this improvement the attachment of the spindle-tip furnishes the bearing for the spring on the latter. The spring therefore can rest directly on the end of the wooden spindle or in the cleft and the desirable metallic bearing for the spring be furnished by the spindle-tip when connected with the spindle.

While the construction above described is that which I deem preferable, the form of tip and connection of spring with the spindle may be varied from that shown without departing from the spirit of my invention so long as the attachment of the spindle-tip with the spindle furnishes the bearing for the end of the spring or so long as the bearing is furnished by the spring impinging or resting against the diagonally-opposite edges of the forked projections of the spindle-tip.

What I claim is—

1. In a spring shade-roller, in combination, a spindle; a metallic end member attached thereto provided with forked projections by which it is secured to the end of the spindle; and a spring mounted on the spindle, one

end of which is adapted to be secured to the roller, and the other end of which is connected to the spindle, and held and rests between the forked ends of the end member whereby the spring impinges and bears against the diagonally-opposite edges of the forked projections, substantially as and for the purposes described.

2. In a spring shade-roller, in combination, a spindle 1; a spindle-tip 5 provided with the forked projections 9 whereby it is secured to the end of the spindle; and a spring 3 mounted on the spindle, the inner end of which is adapted to be secured to the roller, and the outer end of which is connected to the spindle and held and rests between the forked projections 9 of the spindle-tip, whereby the spring impinges and bears against the diagonally-opposite edges of the forked projections, substantially as and for the purpose described.

3. In a spring shade-roller, in combination, a spindle 1, having the cleft 2 in one end; an end member attached thereto provided with forked projections 9 whereby it is secured to the end of the spindle; and a spring mounted on the spindle, one end of which is adapted to be secured to the roller, and the other end of which rests in the cleft 2 in the spindle, and is held between the forked projections 9 of the end member, whereby the spring in the cleft impinges and bears against the diagonally-opposite edges of the forked projections, substantially as and for the purpose described.

4. In a spring shade-roller, in combination, a spindle 1, having the cleft 2 in one end, an end member attached thereto, provided with forked projections 9 and inner web 10 adapted to engage with the cleft 2 in the spindle, whereby the member is secured to the spindle; and a spring mounted on the spindle, one end of which is adapted to be secured to the roller, and the other end of which rests in the cleft 2 in the spindle, and is held between the forked projections 9 of the end member, whereby the spring in the cleft impinges and bears against the diagonally-opposite edges of the forked projections, substantially as and for the purpose described.
